UNITED STATES PATENT OFFICE

2,541,716

UNITARY TRANSMISSION FOR HAIR CLIPPERS

John Oster, Racine, Wis., assignor to John Oster Manufacturing Company, Racine, Wis., a corporation of Wisconsin

Application February 23, 1945, Serial No. 579,421

3 Claims. (Cl. 74—50)

1

This invention relates to hair clippers and refers particularly to clippers of the electric motor type forming the subject matter of Patent No. 2,182,597, issued to John Oster, December 5, 1939.

In these clippers the comparatively small electric motor is housed within a body which serves as a handle for the clipper, and the cutting assembly comprising cooperating stationary and movable cutters is detachably carried at the forepart of the body to be driven by the armature shaft of the motor through a suitable transmission. In the past, it has been the practice to employ a medially pivoted lever in the transmission means oscillated about its pivot by rotation of the drive shaft and having a tongue at its forward end projecting into a drive socket in the movable cutter to reciprocate the cutter upon oscillation of the lever.

This manner of driving the movable cutter is objectionable inasmuch as it requires the tongue at the forward end of the drive lever to have a more or less cylindrical surface for engagement with the sides of the driving socket in the movable cutter in order to accommodate for the relative movement between the tongue and cutter during oscillation of the lever.

Hence, a wiping engagement on a substantially line contact exists between the driving tongue and the side walls of the driving socket in the movable cutter which makes rapid wear on the tongue of the driving lever inevitable.

Moreover, unless the cylindrically shaped tongue fits substantially snugly between the sides of the driving socket in the movable cutter a clattering develops during operation of the clipper because of the play at the point of connection between the lever and movable cutter which obviously becomes more noticeable and objectionable as wear on the tongue increases.

With these objections to past constructions in mind, it is an object of the present invention to improve the manner in which the movable cutter is driven so as to minimize wear at said driving connection and thereby largely prevent noisy operation or clattering.

More specifically it is an object of this invention to provide a hair clipper of the character described with a driving arm for the movable cutter constrained to reciprocatory movement so as to enable substantially flat parallel surfaces on the tongue of relatively large area to engage corresponding flat surfaces on the movable cutter and to eliminate wiping engagement therebetween.

A further object of this invention is to pro-

2

vide unitary driving mechanism interposed between the movable cutter and the drive shaft of the clipper for translating rotation of the drive shaft into reciprocation of the movable cutter.

5 With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawings illustrate two complete examples of the physical embodiment of the invention constructed in accordance with the best modes so far devised for the practical application of the principles thereof and in which:

15 Figure 1 is a side elevational view of the forepart of a hair clipper having portions broken away and in section to illustrate the unitary drive transmission of this invention;

20 Figure 2 is a top view of the clipper shown in Figure 1 with part of the cover broken away to better illustrate the drive transmission;

25 Figure 3 is a perspective view illustrating the drive transmission disassembled as a unit from the forepart of the body of the clipper;

30 Figure 4 is a perspective view of portions of the handle and the forepart of the body shown separated to illustrate the manner of their assembly;

35 Figure 5 is an exploded perspective view of the drive transmission showing its parts in the order of their assembly; and

Figure 6 is a side elevational view of a clipper similar to that of Figure 1 but provided with a modified type of cutting blade assembly.

40 Referring now more particularly to the accompanying drawings in which like numerals indicate like parts, the numeral 10 designates the body of the clipper. The body 10 serves to house an electric motor (not shown) and acts as a handle for the clipper.

45 The body is extended forwardly as at 11 and mounts a cutting assembly 12 at its forward extremity for ready detachment as by means of a screw 13. The drive transmission 14 of this invention is interposed between the armature or power shaft 15 of the clipper and the movable cutter 16 of the cutting assembly to translate rotation of the power shaft into reciprocation of the movable cutter. As clearly illustrated in Figures 1 and 3, the driving transmission 14 is of

unitary nature and is received within a cavity 17 formed in the forepart 11 of the body.

The drive transmission includes a substantially U-shaped frame 18 having a base 19 adapted to lie flatwise along the bottom of the cavity 17 to be secured therein by screws 20 passing through holes in the forepart 11 and threaded into the base 19. The sides of the U-shaped frame provide transversely spaced standards 21 located at opposite sides of the axis of the power shaft 15, which it is to be noted, has its forward end projecting into the cavity 17 to be received between the standards. The standards 21 cooperate to support a cutter actuating arm 22 therebetween by means of parallel, transverse guide pins 23 pressed into suitable holes 24 formed in downwardly depending flanges 25 at the side edges of the arm with the pins slidably received in bushings 26 carried by the standards.

The axes of the guide pins 23 lie in a common plane parallel to the plane of the base 19 and are spaced apart substantially in the direction of the axis of the power shaft 15 to thus constrain the driving arm 22 to translating motion in a path parallel to the base but crosswise of said axis of the drive shaft 15 and extending in the same direction as the path of movement of the movable cutter 16.

A tongue 27 on the forward extremity of the arm 22 engaged in the conventional driving socket 28 cut into the movable cutting blade 16 assures bodily reciprocation of the arm and cutter 16 in unison. Attention is directed to the fact, however, that the sides 29 and 30 of the tongue and socket respectively are parallel and flat to provide substantial bearing area in the driving connection between these parts.

This desirable feature largely eliminates wear at the engaging surfaces of the tongue and socket to thereby preclude the clattering previously experienced upon development of such wear. These features are attained chiefly because of the reciprocating motion of the drive arm 22 and the consequent elimination of relative movement between it and the cutter 16 during operation such as was the case with the oscillating type drive lever heretofore in use.

An upright spindle 31 carried by the base 19 medially between the standards 21 and substantially in line with the shaft 15 provides a bearing for a bevel gear 32 having a hub 33 telescoped over the spindle 31. The gear 32 meshes with a bevel pinion 34 on the forward extremity of the drive shaft 15 and rotation of the driven gear 32 by means of the bevel pinion is translated into reciprocation of the driving arm 22 on its guides by means of a block 35 journaled on a pin 36 carried eccentrically by the bevel gear 32.

The block 35 has a width to slidably but snugly engage between the flanges 25 of the driving arm and it is to be noted that wear between the block and these flanges is held to a minimum by engagement of relatively large flat areas on the block and flanges.

Hence, it will be seen that in the operation of the clipper, rotation of the drive shaft effects rotation of the driven gear 32 which in turn causes the driving arm 22 and the movable cutter connected therewith to be laterally reciprocated as a unit.

It is also to be noted that the driving transmission 14 may be readily replaced or removed for repair as a unit to greatly simplify maintenance of the clipper.

The frame 18 in the present case also carries 75

the cover 37 for the transmission which is secured in position on the forepart 11 of the body covering the cavity 17 by means of screws 38 passing through suitable apertures in the cover and threaded into suitable holes 39 in the standards. The forward end of the cover has portions bent downwardly as at 39' to form a guard for the cutting assembly in the conventional manner.

In previous clipper constructions it was the custom to provide for detachment of the forepart 11 of the body from the handle portion 10 by means of screws passing through one of these sections to be threadedly received in the other. In the present instance, however, a novel and much more convenient detachable connection between these parts is provided as illustrated in Figure 4.

As herein shown the handle portion 10 has a pilot 40 projecting axially from its front end portion snugly but rotatably receivable in a bore 41 formed in the rear of the forepart 11 of the clipper. The pilot 40 is circumferentially recessed as at 42 at substantially diametrically opposite points to receive pins 43 embedded in the rear of the forepart 11 so as to project radially into the bore 41.

These pins are adapted to engage behind spring arms 44 secured to the end surface of the pilot 40 and overhanging the circumferentially recessed portions 42. If desired, the spring arms may be indented as at 45 so that they snap over the pins 43 upon rotation of the forepart 11 on the pilot 40 to bring the pins from initial positions in the recesses under the arms 44.

This manner of detachably connecting the forepart of the body to the handle portion 10 is exceedingly simple and advantageous in that it readily enables detachment of the entire driving head for substitution in the case of damage thereto or for replacement of the head by a shaving head or the like.

In Figure 6 a slightly modified form of cutting assembly 12' is provided which is identical to that illustrated in the aforementioned patent to John Oster. In this instance it will also be seen that the advantages derived from the employment of a bodily reciprocating drive arm 22 are retained despite the provision of a slightly modified form of cutting assembly.

From the foregoing description taken in connection with the accompanying drawings, it will be readily apparent that this invention provides a greatly improved driving mechanism for hair clippers and which is constructed to operate with a minimum of noise and of wear on the driving arm.

What I claim as my invention is:

1. Transmission mechanism adapted to be received within a cavity in the forepart of the body of a hair clipper to translate rotation of the drive shaft of the clipper into reciprocation of the movable cutter of the cutter assembly carried at the forepart of the clipper body, comprising: a relatively flat base adapted to be readily detachably secured in the bottom of said cavity at a level beneath the level of the drive shaft; a pair of standards extending upwardly from opposite sides of the base, said standards being spaced laterally from one another and adapted to receive the forward end of the drive shaft therebetween; a spindle having one end anchored in the base and extending perpendicularly upwardly therefrom between said standards, said spindle being adapted to be disposed substantially in line with the drive shaft crosswise of the axis thereof when the transmission mecha-

nism is in place on the clipper; a gear journalled for rotation on said spindle and adapted to mesh with a suitable driving gear on the drive shaft so that the spindle gear may be rotated by the drive shaft; an eccentric pin carried by the spindle gear; an elongated cutter actuating arm carried by said standards with the arm positioned lengthwise between them and constrained to sidewise translating motion in a path above the spindle and substantially normal to the axis thereof; flanges on the cutter actuating arm disposed at opposite sides of said eccentric pin; a block journalled on said eccentric pin and engaging between said flanges to translate rotation of the spindle gear into sidewise reciprocatory movement of the cutter actuating arm; and a tongue on the end of the cutter actuating arm which is disposed adjacent to the movable cutter when the transmission mechanism is in place on the clipper connectible with the movable cutter.

2. Transmission means for translating rotation of the drive shaft of a hair clipper into reciprocation of the movable cutter of the cutter assembly at the forepart of the clipper body, comprising: a substantially U-shaped frame readily detachably securable to the forepart of the body inside a cavity therein with the closed end of the frame against the bottom of the cavity and with the sides of the frame providing laterally spaced standards adapted to project up from the bottom of the cavity at opposite sides of the forward end of the drive shaft; an elongated cutter actuating arm positioned lengthwise between said standards and supported therefrom for sidewise reciprocatory motion across the space between the standards and in a path spaced a distance above the closed end of the U-shaped frame; a gear supported by the frame between said standards and beneath the cutter actuating arm for rotation on an axis fixed with respect to the frame and substantially normal to the path of reciprocatory motion of the cutter actuating arm, said gear being adapted for meshing engagement with a pinion on the drive shaft of the clipper; means driven by said gear and engaged between spaced abutments on the actuating arm for translating rotation of the gear into

sidewise reciprocatory motion of the arm in said path; and a driving projection on the end of the cutter actuating arm which is disposed adjacent to the cutter assembly when the transmission means is in place on the clipper connectible with the movable cutter.

3. Transmission means adapted to be interposed between the cutter assembly and the drive shaft of a hair clipper for translating rotation of the drive shaft into reciprocation of the movable cutter, comprising: a frame readily detachably securable within a cavity in the body of the clipper and including a relatively flat base adapted to lie at the bottom of said cavity at a level beneath the level of the drive shaft; a rotatable member carried by the frame for rotation on an axis fixed with respect thereto and normal to said base; means on said rotatable member for drivingly connecting the same with the drive shaft; an elongated cutter actuating arm; means mounting said arm on the frame in spaced superimposed relationship to the base, and for sidewise reciprocatory motion in a fixed path laterally across the base and substantially normal to the axis of said rotatable member; means connected between said arm and the rotatable member for translating rotation thereof into reciprocatory movement of the arm in said path; and means on the end of the arm which is disposed adjacent to the movable cutter when the transmission means is in place on the clipper adapted for engagement with said reciprocable cutter to impart reciprocatory motion thereto.

JOHN OSTER.
